(57) **CLAIM**

I claim the ornamental design for a sprinkler nozzle insert tree, as shown and described.

DESCRIPTION

The present application is related to and claims priority to U.S. Utility Application Ser. No. 10/883,940, filed Jul. 2, 2004, and titled “Sprinkler Nozzle Insert Assembly”.

FIG. 1 is a perspective view of a sprinkler nozzle insert tree according to my new design, the broken lines of which are for illustrative purposes only and form no part of the claimed design;

FIG. 2 is a plan view of the sprinkler nozzle insert tree of FIG. 1, the broken lines of which are for illustrative purposes only and form no part of the claimed design;

FIG. 3 is a right side elevational view of the sprinkler nozzle insert tree of FIG. 1 and the left side is identical thereto;

FIG. 4 is a front elevational view of the sprinkler nozzle insert tree of FIG. 1 and the rear side is identical thereto; and,

FIG. 5 is a bottom view of the sprinkler nozzle insert tree of FIG. 1, the broken lines of which are for illustrative purposes only and form no part of the claimed design.
